UNITED STATES PATENT OFFICE.

CHARLES C. BLACKMORE, OF DAYTON, OHIO.

AIRPLANE-BOMB.

1,278,578.

Specification of Letters Patent. Patented Sept. 10, 1918.

Application filed June 24, 1918. Serial No. 241,454.

To all whom it may concern:

Be it known that I, CHARLES C. BLACKMORE, a citizen of the United States, residing at Dayton, in the county of Montgomery and 5 State of Ohio, have invented certain new and useful Improvements in Airplane-Bombs, of which the following is a specification, reference being had therein to the accompanying drawing.

10 This invention relates to an airplane bomb; that is, a bomb or projectile adapted to be dropped from an airplane or the like.

The object of the invention is to provide 15 a bomb of this kind which will scatter explosive missiles, such as hand grenades, over a large area surrounding the point at which the bomb strikes; and, further, to accomplish this without the use of an explosive to eject the missiles.

20 It is also an object of the invention to provide a bomb of this kind which will be simple in construction and operation; which can be easily and safely handled; and which will be positive in its operation.

25 A further object of the invention is to provide means to positively retain the missiles in position in the bomb during the transportation and handling thereof, and to release them at the time of, or immediately following, the discharge of the bomb.

In the accompanying drawings Figure 1 30 is a side elevation, partly broken away, of a bomb embodying my invention; Fig. 2 is a transverse section taken on the line 2—2 of Fig. 1 looking in the direction of the arrows; Fig. 3 is an enlarged section broken away taken on the line 3—3 of Fig. 2; Fig. 4 is a front elevation, partly broken away, showing the retaining cover; and Fig. 5 is a 35 side elevation of the same partly in section.

In these drawings I have illustrated one 40 form of my invention and have shown the same as embodied in a structure which I have characterized as an airplane bomb, or projectile, because it is adapted to be dropped or discharged from an airplane after the manner of the usual bomb. Ordinarily, however, the bomb will not be of an explosive character, although it will be obvious that, if desired, an explosive charge could be added to the bomb itself. As here shown, the bomb comprises a supporting structure, or body portion, having a plurality of compartments, each of which is 45 adapted to contain a missile, such as a hand

grenade. Suitable ejecting means are provided which will be operated by the momentum of the bomb, as it strikes its target, to discharge the missiles from the respective compartments; and which will also render 60 the firing devices operative at the time the missiles are discharged from the compartments. The construction and arrangement of the structure as a whole, as well as the several parts thereof, may take various 65 forms, and the construction and arrangement here shown have been selected for the purpose of illustration only.

In the particular embodiment of the invention here illustrated, I have shown the 70 several compartments as centered about a supporting member which is, preferably, in the form of a hollow rod 10 which not only forms a guide for the actuating device, as will be hereinafter explained, but which supports the several compartments. As here shown, the several compartments are formed by mounting on the central supporting rod a series of transverse partitions 11, each of 75 which forms the bottom of a series of compartments. The outer edges of the several partitions are connected one with the other by vertical standards 12 which constitute braces and impart rigidity to the structure. The space between the adjacent partitions is 80 divided by vertically extending radial partitions 13 into separate compartments, each of which is of a size and shape to accommodate the particular missile for which the projectile is designed. The construction here illustrated is intended more particularly for 85 hand grenades, or similar explosive missiles or bombs, and I have shown such a grenade in conventional form at 14. The number of compartments in each tier, as well as the 90 number of tiers, will, of course, depend upon the size of the projectile and the size of the particular missile which is to be used. In the present instance, the structure is of a comparatively small diameter and each tier 95 contains four compartments which are radially arranged. The compartments of one tier may be so arranged relatively to the compartments of adjacent tiers as to cause the missiles to be discharged in different 100 directions, as by arranging the partitions between the compartments of one tier in planes lying between the partitions of the adjacent compartments, as shown in Fig. 1.

Suitable means are provided for ejecting 110

the missiles from the respective compartments and, preferably, a separate ejecting device is provided for each compartment and the several ejecting devices are operated by a common actuating device, so that the several missiles will be discharged simultaneously. The bomb in the present construction is wholly mechanical in its operation, that is, it does not use an explosive of any kind to accomplish the ejection of the missiles therefrom. Ejecting devices of various kinds may be provided, but I prefer an ejecting device operating on the principle of a lever, one arm of which is arranged in operative relation with the operating device, to which movement will be imparted by the impact of the projectile with its target, which, ordinarily, would be the surface of the ground, or some object immediately adjacent thereto. The other arm of the lever is so arranged with relation to the missile that the movement imparted to the lever by the actuating device will cause the missile to be ejected from its compartment. Not only is such an ejecting device simple in construction and positive in its operation, but the missiles of different compartments, or different tiers, can be caused to be thrown different distances by so arranging the lever with relation to its fulcrum as to increase or decrease the operative length thereof, with a corresponding increase or decrease of power as applied to the missile. The ejecting device here shown is in the form of a double-armed lever 15 which is substantially V-shaped in construction and is pivoted at a point near its apex on the partition 11 forming the bottom of the compartment. For the sake of compactness, the partition or bottom wall of the compartment is slotted and the ejecting lever is arranged partly within the slot. The one arm of the lever, 16, extends through a vertical slot 17 in the hollow central rod 10 and into a position to be engaged by a shoulder formed on an actuating device or vertically movable rod 18, which is slidably mounted in the hollow supporting rod 10. The shoulder, or stop, with which the lever cooperates may be formed in any suitable manner, and, in the present construction, it is formed by providing a rod 18 in a circumferential groove, thus providing a single shoulder which will actuate the ejecting levers of the four compartments of the adjacent tier, and which will be in operative engagement with the several levers regardless of any rotatory movement which may be imparted thereto. The other arm 19 of the ejecting lever is arranged to engage the missile and forcibly eject the same from its compartment when the lever is operated by the actuating device. In the present construction I have shaped the arm 19 of the lever to form a seat upon which the missile rests, but this is an optional construc-

tion and may not be desirable in all cases. The hand grenade, now in common use, is provided with firing devices which are normally retained in an inoperative position by means of a firing pin, which is indicated conventionally at 20. The withdrawal of this pin renders the firing devices operative and they may be adjusted to cause the explosion of the grenade at a specified time after the pin has been withdrawn, which takes place just as the grenade is thrown. The present device is provided with means for withdrawing the firing pins, and thus rendering the firing devices operative, as the grenade is ejected from its compartment. In the present instance the end of the firing pin is engaged with the end of the arm 19 of the ejecting lever when the grenade is placed in position in its compartment, and when the grenade is ejected the pin remains fastened to the arm of the lever and is thus withdrawn as the grenade is ejected, the arrangement of the arm with relation to the pin being such that at the end of the movement of the lever the pin will project in substantially the line of movement of the grenade.

The actuating device 18 extends beyond the lower end of the hollow supporting rod 10 and is capable of vertical movement relatively to the hollow rod. Consequently, when the bomb is dropped point downward, the end of the actuating rod 18 will engage the target and its movement will be checked before the movement of the body portion of the structure is checked. The sudden stopping of the actuating rod acts upon the ejecting levers in the manner of a violent blow and rocks the same about their axes with great force and rapidity, thus imparting to the grenades an ejecting force sufficient to project them for a considerable distance. As has been above stated, the amount of force applied to the grenade and, consequently, the distance which it is projected, may be varied by a proper adjustment of the lever with relation to its fulcrum. In the present instance, this has been accomplished by shortening the arm 19 of the lever where a short throw is desired. It will be apparent that if the levers near the lower end of the structure are adjusted to throw the missiles a short distance, and the levers of the succeeding compartments, above the first-mentioned compartments, are adjusted to throw the missiles increasing distances, that the missiles can be scattered over a large area surrounding the point where the bomb strikes. The space between the bottom wall of the lower compartment and the lower end of the hollow supporting rod, which projects some distance below said bottom wall, is inclosed by a conical cover which gives to the lower end of the bomb a pointed shape, as shown at 21, and the upper end of the bomb is provided with the usual fins 22 to cause it

to assume a vertical position during its movement downward.

It is possible to eject the missiles from the compartments without the use of a positively actuated ejecting device, and it may sometimes be desirable to eject a part, or all, of the missiles in this way. In the present construction I have shown the two lowermost tiers of compartments as having their bottom walls or floors sloped downwardly and outwardly in such a manner that when the body of the structure is brought to a sudden stop the missiles will continue to move and will be thus ejected from their compartments and will be projected a distance from the structure, depending upon the angle of inclination imparted to the bottom wall of the compartment. As here shown, the bottom wall of the lower tier of compartments is inclined at a sharper angle than is the bottom wall of the succeeding compartment. Thus, the missiles from the lower compartments will be projected a less distance than will the missiles from the second compartment. The firing pins may be withdrawn from the missiles by merely attaching them to a fixed stop in the compartment after the manner in which they are attached to the levers of the ejecting devices.

I have shown the device in Figs. 1, 2 and 3 as provided with resilient fingers or spring clips 23 fixed to the side walls of the respective compartments and embracing the missiles to retain the same therein. The strength of these fingers is sufficient to prevent the displacement of the missiles by gravity or slight jars which may be imparted thereto in handling. However, to make the device absolutely safe to handle, it is desirable that some means be provided to positively prevent the displacement of the missiles, and the consequent withdrawing of the firing pins, during transportation or rough handling. This I prefer to accomplish by providing an inclosing envelop for the structure as a whole which will close the outer ends of the compartments and thus effectually retain the missiles therein. It is, of course, necessary that this inclosing envelop should be removed before the bomb strikes the ground and it is preferable that this should be accomplished automatically. Of course, the bomb could be slid out of the envelop when it is discharged, but a more satisfactory method is to form the envelop of a sheet of metal 25 which is bent about the projectile and its edges attached one to the other to retain it in cylindrical form, and to provide means for automatically disconnecting the edges of the sheet to permit the same to spring apart and thus separate the closure from the projectile. This may be accomplished in various ways. As shown in Figs. 4 and 5, I have overlapped the edges of the sheet and have connected the same

at the upper end of the envelop by means of a pin 26 which is screw-threaded into a socket 27, preferably formed in a plate which is secured to one edge of the sheet by means of rivets or the like, and has an unthreaded lower end which projects into a socket 28, secured in a similar manner, to the other edge of the sheet, the latter edge of the sheet being notched to permit the socket 27 to extend into alignment with the socket 28. Attached to the upper end of the screw-threaded pin or bolt 26 is a fan or small propeller 29 which will be rotated as the projectile moves downwardly through the air, thus unscrewing the pin and withdrawing the lower end thereof from the socket 28. The overlapped edges of the sheet may be connected at the lower end thereof in the same or any suitable manner, but I prefer simply to notch the edges of the sheet, as shown at 30, to receive a lug 31 secured to the body of the projectile near the bottom thereof. When the edges of the sheet have been overlapped, the notches will be brought into alignment and the lug will be brought into engagement therewith as the cover is fitted into position on the bomb. When the edges of the sheet are released at the upper end of the envelop by the withdrawal of the pin 26 they will spring apart, due to the resiliency of the metal, and this will cause the notches 30 at the lower end to be disengaged from the lug, thus releasing the edges of the envelop along its full length and permitting the same to open out and fall away from the bomb. To prevent the envelop from working up lengthwise of the bomb, away from the lug 31, a stud or stop 32 may be secured to the structure near the upper end thereof adjacent to the edge of the envelop or retaining cover. So long as this stud is not in frictional engagement with the edge of the sheet, it will not interfere with the separation of the edges thereof and the removal of the envelop from the structure. I prefer to mount the fan 29 on one edge of the sheet from which the envelop is formed so that it will be separated from the structure along with the envelop and will in no way interfere with the flight of the structure.

The operation of the device will be readily understood from the foregoing description and it will be apparent that a bomb of this kind dropped from an airplane or the like will strike the ground with great force, thus operating the projecting devices and causing the missiles to be scattered over a relatively large area surrounding the projectile. And, inasmuch as the hand grenade is effective over a considerable area, it will be apparent that the explosion of the missiles will effectively cover this entire area.

While I have shown and described one embodiment of my invention, I wish it to be understood that I do not desire to be limited

to the details thereof, as various modifications will occur to a person skilled in the art. Having now fully described my invention, what I claim is new and desire to be secured by Letters Patent, is:

1. In an airplane bomb, the combination with a structure adapted to carry a plurality of missiles, of mechanism actuated by the momentum of said bomb to eject said missiles from said structure.
2. In an airplane bomb, the combination with a structure adapted to carry a plurality of missiles, of mechanism actuated by the momentum of said bomb to eject said missiles from said structure, and to throw different missiles different distances from said structure.
3. In an airplane bomb, the combination with a structure adapted to carry a plurality of explosive missiles having normally inoperative firing devices, of mechanism actuated by the momentum of said bomb to eject said missiles from said structure and render said firing devices operative.
4. In an airplane bomb, the combination with a structure adapted to carry a plurality of explosive missiles having normally inoperative firing devices, of a mechanically operated ejecting device actuated by the momentum of said bomb to eject the missiles therefrom and to render said firing devices operative.
5. In an airplane bomb, the combination with a structure adapted to carry a plurality of grenades, each having a firing pin, of a mechanically operated ejecting device operated by the impact of said bomb with its target to eject the missile from said structure, and a connection between said ejecting device and said firing pin to cause the latter to be withdrawn as the missile is ejected.
6. In an airplane bomb, the combination with a structure adapted to carry a plurality of missiles, of a mechanically operated ejecting device for each of said missiles and an actuating device connected with said ejecting devices and arranged to be operated by the impact of said bomb with its target.
7. In an airplane bomb, the combination with a structure adapted to carry a plurality of missiles, of mechanically operated ejecting devices for said missiles and an actuating rod adapted to be operated by the impact of said bomb with the target, said rod being operatively connected with said ejecting devices.
8. In an airplane bomb, the combination with a structure adapted to support a plurality of missiles in superimposed tiers, an actuating rod extending lengthwise of said structure and adapted to be operated by impact, and mechanism actuated by said rod for ejecting said missiles from said structure.
9. In an airplane bomb, the combination

with a structure adapted to support a plurality of missiles in superimposed tiers, an actuating rod extending lengthwise of said structure and adapted to be operated by impact, and mechanism actuated by said rods for ejecting said missiles from said structure, said ejecting means being so arranged that the missiles of some tiers will be thrown greater distances than the missiles of other tiers.

10. In an airplane bomb, the combination with a structure adapted to carry a plurality of missiles in superimposed tiers, a pivoted ejecting device for each of said missiles, and an actuating rod operatively connected with each of said ejecting devices and arranged to be operated by the impact of said bomb with its target.

11. In an airplane bomb, the combination with a structure adapted to carry a plurality of missiles, of a two-armed lever pivotally mounted adjacent to each of said missiles and having one arm arranged to eject the missile when said lever is moved about its axis, and an actuating rod arranged in operative relation with the other arm of said lever and adapted to be operated by the impact of said bomb with its target.

12. In an airplane bomb, a structure comprising a plurality of superimposed compartments, an actuating rod extending lengthwise of said structure adjacent to said compartments, an ejecting device pivotally mounted adjacent to each compartment and having one arm arranged to engage the missile in said compartment, and having its other arm arranged to be engaged by said actuating rod.

13. In an airplane bomb, a structure comprising a hollow supporting member, a plurality of partitions carried by said supporting member to form compartments arranged in superimposed tiers, an actuating rod mounted in said hollow supporting member and arranged to be operated by the impact of said bomb with its target, an ejecting lever pivotally mounted in each compartment and having one arm arranged to engage a missile in said compartment, and having its other arm extending into said hollow supporting member and into operative relation with said actuating rod.

14. In an airplane bomb, a structure comprising a hollow supporting member, a plurality of partitions carried by said supporting member to form compartments arranged in superimposed tiers, an actuating rod mounted in said hollow supporting member and arranged to be operated by the impact of said bomb with its target, an ejecting lever pivotally mounted in each compartment and having one arm arranged to form a seat for a missile, and having its other arm extending into operative relation with said actuating rod.

15. In an airplane bomb, a structure comprising a hollow supporting member, partitions carried by said supporting member and arranged to form a plurality of compartments, each adapted to receive an explosive missile having a firing pin, an ejecting lever pivotally mounted in each of said compartments and having one arm arranged to engage the missile in said compartment and to be 5 connected with the firing pin of said missile, and having its other arm extending into said hollow supporting member, and an actuating rod mounted in said hollow supporting member in operative relation with the last- 10 mentioned arm of said lever.
16. In an airplane bomb, a structure comprising a series of transverse and vertical partitions arranged to form compartments for missiles, said compartments being arranged in superimposed tiers, and the vertical partitions of one tier of compartments being arranged in planes differing from the planes of the vertical partitions of an adjacent tier of compartments, and means for 15 ejecting the missiles from said compartments.
17. In an airplane bomb, the combination with a structure having a plurality of compartments, each adapted to receive a missile, 20 of an ejecting device arranged in each compartment to eject the missile therefrom, an actuating device for said ejecting devices, and resilient clips carried by the walls of the compartment to hold said missiles against 25 displacement.
18. The combination with a bomb comprising an elongated body structure having a plurality of compartments, each adapted to contain a missile, of an envelop adapted 30 to surround said body structure to retain the missiles therein, and means for causing said envelop to be separated from said body structure.
19. In an airplane bomb, the combination 35 with a structure having a plurality of radial compartments, each adapted to receive a missile, of a retaining cover comprising a sheet of resilient material bent about said structure to retain the missiles in said compartments, means for connecting the edges 40 of said sheet one to the other, and means to automatically disconnect said edges of said sheet.
20. In an airplane bomb, the combination with a structure having a plurality of compartments, each adapted to receive a missile, 45 of a retaining cover comprising a sheet of resilient material bent about said structure to retain the missiles in said compartments, a locking pin to connect the edges of said sheet of material one to the other, and a fan 50 connected with said locking pin and adapted to be operated by the flight of said bomb through the air to withdraw said locking pin and release said retaining cover.
21. In an airplane bomb, the combination with a structure having a plurality of compartments adapted to contain missiles, of a retaining cover comprising a sheet of resilient material bent about said structure to 55 retain the missiles in said compartments, the lower end of said sheet having notches therein adapted to be brought into alignment one with the other when the vertical edges of said sheet are overlapped, a lug carried by 60 said structure and adapted to enter said aligned notches, a locking pin screw-threaded on to said sheet near one edge thereof, a socket carried by the other edge of said sheet and adapted to receive said locking 65 pin, and a fan connected with said locking pin and adapted to be actuated by the flight of said bomb through the air to move said locking pin out of said socket.
- In testimony whereof, I affix my signature 70 hereto.

CHARLES C. BLACKMORE.
